UNITED STATES PATENT OFFICE.

CHARLES VERO, OF AATHERSTONE, COUNTY OF WARWICK, ENGLAND,
ASSIGNOR OF ONE-HALF TO JAMES EVERITT, OF SAME PLACE.

MANUFACTURE OF FELT HATS.

SPECIFICATION forming part of Letters Patent No. 351,226, dated October 19, 1886.

Application filed June 7, 1886. Serial No. 204,416. (No specimens.)

To all whom it may concern:

Be it known that I, CHARLES VERO, a subject of the Queen of Great Britain, residing at Atherstone, in the county of Warwick, England, felt-hat manufacturer, have invented certain new and useful Improvements in the Manufacture of Felt Hats, of which the following is a specification.

This invention has for its object improvements in the manufacture of felt hats.

I make the upper part and crown of the hat and the brim of the hat of different materials, and in the operations of felting or hardening I combine these into one fabric. Usually I make the crown and upper part entirely of fur, while the brim I make of wool. Wool may, however, in some cases, be mixed with the fur of which the crown and upper part are formed, and, on the other hand, the wool forming the brim may, in some cases, be plaited with fur, or a proportion of fur may be mixed with the wool of which the brim is made; but in all cases the material which I employ for the crown and upper part is different from that for the brim, and the two are thoroughly combined into one fabric in the operation of felting or hardening.

The way in which I prefer to operate is as follows: I first blow the fur to form the crown and upper part of the hat onto a perforated cone, from the interior of which air is exhausted, as is usual in the manufacture of hats entirely of fur; but I accumulate the fur onto a smaller surface than would be necessary if the hat were to be entirely of this material. I then proceed, as usual, to wrap cloths around the fur upon the cone and to place a metal cover over it. While the fur is so held I saturate it and the cloths wrapped around it with water. The fur can then be removed without injury. When several fur crowns have been thus produced, they are formed into a bundle and manipulated in the usual way to give sufficient consistence to the material to enable it to hold together when dry. The crowns are then dried and placed on one side. For the brim of the hat I accumulate a bat of wool coming from a carding-engine onto a double cone in the manner usual in making woolen hats, except that no care is requisite to cover the ends of the double cone. When sufficient

wool has been accumulated, it is cut off from the cones in the usual way, and so two brims are formed, and they are trimmed into shape. The fur crown is now brought to the brim and is placed in position so as to overlap it, the materials being, if desired, thinned to some extent where they overlap at the band, to prevent too great a thickness at this part. An inlayer or separating fabric is now put inside the hat-body, and this is then worked in a machine known as a "flat hardener," which commences the felting in the center portion of the body without pressing upon the tip or the folded or doubled edges. Under this treatment the fur crown immediately unites with the woolen brim. After a short time the inlayer or separating fabric is removed from the interior, the hat-body is crozed or refolded, the inlayer is again inserted, and the operation is repeated, so a complete union between the fur crown and the woolen brim is effected all round the hat-body. The operations of completing the hat are then as usual.

A like result may be obtained by blowing a brim of a mixture of wool and fur onto the cone, and at a separate operation blowing fur onto the cone to form the upper part and crown of the hat, this upper portion of the cone having previously been kept bare by any suitable covering.

It will be seen that my improvement in felt hats, consisting in independently forming the crown and brim and felting them together, differs essentially from the heretofore practiced method of separately making the crown and the brim and then uniting them by sewing, or by eyelets or by cement.

I claim—

1. A felt hat consisting of the independently-formed crown and brim, of different materials, united into one by felting them together, substantially as set forth.
2. A felt hat having a crown or upper part of fur or fine material and a brim of wool or coarser material, the two combined and forming one continuous felted fabric, substantially as set forth.

CHARLES VERO.
